UNITED STATES PATENT OFFICE

2,037,393

VENETIAN BLIND

Lee R. Roberts, Chicago, Ill., assignor, by direct and mesne assignments, to himself and Frank Kemptner, Chicago, Ill.

Application April 23, 1934, Serial No. 721,927

23 Claims. (Cl. 156—17)

This invention relates to window blinds or shades, and particularly to devices of the character described, commonly known as "Venetian blinds", wherein a plurality of slats are flexibly connected together in a manner to permit of their being positioned closely together in inoperative position, or spaced bodily a substantial distance relatively to each other in operative position and capable of being tilted at substantially uniform angles.

One object of the present invention is to provide a device of the character described, wherein the slats are successively moved into operative position adjacent the lower portion of the device, and wherein the slats are successively moved into inoperative position adjacent the upper portion of the device.

Another object of the invention is to provide a device of the character described, wherein the slats when in inoperative position, are supported and retained in a group adjacent the upper portion of the device, and wherein the lowermost slats of the group may be moved successively from the lower side of the group into operative position adjacent the lower portion of the device.

Another object of the invention is to provide a device of the character described having spacing means, and wherein the slats are provided with automatically actuated means cooperable with the spacing means for spacing the slats longitudinally thereof and with respect to each other in operative position.

Another object of the invention is to provide a device of the character described, wherein the automatically actuated means on the respective slats are cooperable with supporting means on adjacent slats and with the spacing means for supporting the slats closely adjacent each other in inoperative position.

Another object of the invention is to provide novel supporting and spacing means for the slats.

Another object of the invention is to provide novel means for tilting the slats and the device as a whole.

Another object of the invention is to provide suitable guides for maintaining the slats in substantially vertical alignment when in either operative or inoperative position.

A further object of the invention is to provide novel means for conveniently mounting the slats for operation in the device.

A still further object of the invention is to improve devices of the character described in

sundry details hereinafter referred to and particularly pointed out in the appended claims.

One embodiment of the invention is shown for illustrative purposes in the accompanying drawings, in which

Fig. 1 is an elevational view of my improved blind construction, illustrating its application to an opening in a wall, such, for example, as a window or the like;

Fig. 2 is an enlarged transverse sectional elevational view taken substantially as indicated by the line 2—2 of Fig. 1;

Fig. 3 is a fragmentary transverse sectional elevational view of a portion of the structure illustrated in Fig. 2, and showing various parts thereof in changed or tilted position;

Fig. 4 is a fragmentary transverse sectional elevational view of a portion of the structure illustrated in Fig. 1, and taken substantially as indicated by the line 4—4 thereof;

Fig. 5 is an enlarged fragmentary sectional elevational view of a portion of the structure illustrated in Figs. 1 and 2, and taken substantially as indicated by the line 5—5 of Fig. 2;

Fig. 6 is a fragmentary plan sectional view of the structure illustrated in Fig. 5, and taken substantially as indicated by the line 6—6 thereof;

Fig. 7 is a plan sectional view of a portion of the structure illustrated in Figs. 1 and 2, and taken substantially as indicated by the line 7—7 of Fig. 1;

Fig. 8 is an enlarged elevational view of a portion of the structure illustrated in Fig. 1 showing the construction and relationship of slat supporting means forming a part of the present invention;

Fig. 9 is a fragmentary transverse sectional elevational view taken substantially as indicated by the line 9—9 of Fig. 8;

Fig. 10 is a fragmentary plan sectional view taken substantially as indicated by the line 10—10 of Fig. 8; and

Fig. 11 is a detail sectional view showing means for mounting the slats in my improved blind construction.

In Figs. 1, 2 and 7 of the drawings, the present invention is shown applied to a window casing, or the like, indicated as a whole by the numeral 15, and having a top portion 16 and side portions 17. 50

Mounted adjacent the respective side portions 17 of the casing 15 are a pair of guide members 18, and mounted adjacent the upper end of the casing 15 at opposite sides thereof, and secured preferably to the top portion 16 by means of 55

screws 19 are a pair of supporting hangers each indicated as a whole by the numerals 21 and 22, respectively, the hangers 21 and 22 being provided, respectively, with side portions 23 and 24, 5 adapted to engage a portion 25 of the guide members 18 to assist in maintaining the hangers 21 and 22 in substantially vertical position.

The respective hangers 21 and 22 are also provided with inwardly extending hollow trunnions 10 26 and 27, respectively, on which a main supporting frame 28 is rotatably mounted, the frame 28 being provided adjacent one of its ends with a sheave 29 and having a spring roller 31 of ordinary, well-known curtain-roller type construction mounted in bearings 32 and 33 carried by the main supporting frame 28 and having a non-rotatable shaft portion 34, as is common practice in spring roller construction, the outer end portion of the shaft 34 being shown 20 in the present instance as mounted in, and secured against rotation with respect to the bearing member 32.

Rotatably mounted adjacent the longitudinal side portions of the supporting frame 28 at opposite sides of the roller 31 are a plurality of guide rollers 35, and pivotally mounted on the axes of the respective guide rollers are a plurality of tape guides 36 adapted to hang downwardly from the longitudinal edge portions of 30 the supporting frame 28 and to be pivotally movable relatively thereto.

Wound on and connected at their ends to the spring roller 31, and extending laterally therefrom at opposite sides thereof, are a plurality of 35 flexible supporting tapes 37 having spaced recesses 38 formed in one of their respective edge portions, the said tapes being trained over the guide rollers 35 and through the downwardly extending tape guides 36, and lower ends of the supporting tapes being flexibly connected by 40 means of staples 39 to the opposite longitudinal edge portions of an actuating bar 41, to which may be connected a pull string 42.

Mounted on and relatively movable with respect to the supporting tapes 37 are a plurality 45 of brackets, each indicated as a whole by the numeral 43, and pivotally connected to the brackets 43 by means of inwardly extending trunnions 44 are a plurality of flexible strips 45 (Figs. 2, 3, 10 and 11) extending between pairs of brackets at opposite sides of the device, and having upwardly extending inturned end portions 46 adapted to receive slats 47 in a manner to support the slats on, and in pivoted relation with 50 respect to the various pairs of brackets 43 at the opposite sides of the blind.

All of the brackets 43 and their associated parts are of substantially identical construction, and by reference to Figs. 8, 9 and 10 it will be 55 apparent that the bracket 43 illustrated therein comprises a casting, or the like, having a vertically disposed open ended slot 48 adapted to slidably receive the tape 37 in a manner to position the recesses 38 thereof adjacent an open end of the slot.

Pivotedly mounted, preferably intermediate its end portions, on a trunnion 49 carried by the bracket 43 is an arm, indicated as a whole by the numeral 51, and extending laterally therefrom adjacent one of its end portions is a connecting pin 52 and a trip pin 53, the connecting pin 52 being adapted to engage the spaced recesses 38 formed in the marginal edge of the tape 37 in a manner to position and support the bracket 43 thereon, the bracket being cut away 70

as indicated at 43a to permit of the engagement, while the connecting pin 52 is normally urged toward the recessed edge of the tape 37 by suitable means, shown, in the present instance, as a weighted end portion 54 of the arm 51, thus, it 5 will be observed, that when the connecting pins 52 are positioned in the respective recesses 38 formed in the tapes 37, the various brackets 43 and the several slats 47 connected thereto will be supported on, and substantially uniformly 10 spaced longitudinally of the tapes 37, as clearly shown in the lower portions of Figs. 1 and 2.

For removing the connecting pins 52 from the recesses 38 formed in the tapes 37 in a manner to disconnect the brackets 43 therefrom, each 15 of the brackets 43 and the tape guides 36, are provided with downwardly extending trip lugs 55 having notches 56 formed therein adapted to receive the connecting pins 52 when withdrawn from the recesses 38, it being the function of the 20 trip lugs 55, when a subjacent bracket 43 is moved in an upward direction with reference to the lug, to engage the trip pin 53 in a manner to rock the arm 51 about its pivotal connection on the trunnion 49, thereby moving the connecting pin 25 52 out of the recess 38 of the tape 37 and into the notch 56 in a manner to cause the connecting pin 52 to rest on the upper side of the lug 55 and support the subjacent bracket thereon when the brackets 43 and slats 47 are assembled 30 in a group adjacent the upper portion of the device, in which position the weighted end portions 54 of the arms 51 will have been moved into their uppermost position by means of a neck portion 57 forming a part of the brackets 35 43.

It will be observed from the foregoing description that when the recessed tapes are fully wound on the spring roller 31, that the brackets 43 and slats 47 mounted thereon will be assembled adjacent the upper portion of the device and supported in grouped position by the main supporting frame 28 and hangers 36 mounted thereon by reason of the connecting pins 52 of the respective arms 51 resting on the trip lugs 55 of a 45 superposed bracket 43 or tape guide 36, the connecting pin 52 of the lowermost bracket being supported on a superposed trip lug 55 and being urged against an unrecessed portion of the tape by the weighted end portion 54 of the arm as 50 clearly shown at the upper portion of Fig. 8.

It will be apparent also that as the actuating bar 41 is drawn downwardly in a manner to unwind the tapes 37 from the roller 31, and the lowermost notches 38 formed in the respective 55 tapes 37 are brought into register with the connecting pins 52 of the lowermost brackets 43, the pins 52 will move into the lowermost notches 38 and out of vertical alignment with the lugs 55 of the superposed bracket, in a manner to be 60 supported by the tapes, and the lowermost brackets and slat connected thereto will be separated from the group adjacent the upper portion of the device and moved downwardly with the downward movement of the tapes, and that as the succeeding recesses 38 are brought successively into register with the connecting pins 52 of the next lowermost brackets, the brackets 43 and slats 47 connected thereto will be successively removed from the group and positioned in spaced relation 65 along the tapes 37, as clearly shown in the lower portions of Figs. 1 and 2, thus, it will be observed that by the construction and arrangement shown and described, the slats 47 and their respective brackets 43 are supported and retained in a group 70 75

in inoperative juxtaposition adjacent the upper portion of the device, and that by reason of the relationship of the connecting pins 52 on the arms 51 of the respective brackets 43 and the spaced recesses 38 formed in the edge portions of the respective tapes 37, the lowermost slats and brackets are moved successively from the group and into spaced operative position adjacent the lower portion of the device as the tapes 37 are drawn from the roller 31.

For tilting the slats to inclined position, as illustrated in Fig. 3, suitable means are provided, as clearly shown in Figs. 1, 2, 5, 6 and 7, the said means being shown, in the present instance, as a drum and cable connection operatively related to the sheave 29.

By reference to Figs. 1, 2, 5, 6 and 7, it will be noted that the bracket 22 is provided with a laterally extending bearing member 58 having upper and lower ear portions 59 and 61, respectively, in which is rotatably and slidably mounted a square shaft 62 and slidably mounted on the square shaft 62 in a manner to rotate therewith is a cable drum 63 having a cable 64 wound thereon and adapted to extend around the sheave 29 in a manner to rotate the sheave and main supporting frame 28 connected thereto when the square shaft 62 and drum 63 are rotated by means of a downwardly extending manually actuated 20 rotatable rod 65 having a hand grip or the like (not shown) secured to its lower end portions, and flexibly connected at 66 to a head 67 formed on the lower end portion of the square shaft 62, the end portions of the cable 64 being connected 25 to the drum 63 in such a manner that when the drum is rotated, one portion of the cable will be wound thereon and another portion of the cable unwound therefrom.

For maintaining the slats 47 and main supporting frame 28 in various desired tilted positions of adjustment, the lower ear portion 61 of the bearing member 58 is provided with a plurality of radially disposed apertures 68, see Figs. 5 and 6, adapted to receive a pair of oppositely disposed dogs 69 formed on the upper side of the head 67 of the square shaft 62, the head 67 and dogs 69 being yieldingly urged in an upwardly direction by means of a spring 71 positioned between the upper ear portion 59 of the bearing member 58 and a collar 72 secured to the upper end of the square shaft 62, as clearly shown in Figs. 1 and 2.

It will be apparent from such a construction, that when the head 67 and shaft 62 are drawn downwardly by a pull on the rod 65, the dogs 69 will be withdrawn from the apertures 68 formed in the lower ear portion 61, thereby permitting the rod 65, head 67, square shaft 62 and drum 63 to be rotated in a manner to rotate the sheave 29 by reason of its connection with the cable 64, thereby tilting the main supporting frame 28 and slats 47, by reason of their connection with the tapes 37, to an inclined position as shown in Fig. 3, and upon releasing the downward pull on the hand rod 65, the dogs 69 will be moved into a pair of the apertures 68 and retained therein by the action of the spring 71 to secure the shaft 62 and drum 63 against rotation, and maintain the slats 47 in the desired position of angular or inclined adjustment.

For maintaining the slats 47 in substantially vertical alignment with respect to each other, whether in operative or inoperative position, the actuating bar 41 and slats 47 are provided adjacent their opposite ends with outwardly extending reduced portions 73 adapted to engage ver-

tically disposed slots 74 formed in the guide members 18 secured to the side portions 17 of the casing 15.

If desired, a dust shield 75 may be mounted on the supporting frame 28 in a manner to cover the roller 31, bearings therefor and tapes 37 wound thereon, as clearly shown in Figs. 1, 2, 3 and 4.

It will be observed from the foregoing description, that the present invention provides a novel construction and arrangement wherein the slats are supported and retained in inoperative position in a group adjacent the upper portion of the device, and wherein the lowermost slats of the group are removed successively from the lower side thereof by automatically actuated means mounted on the brackets 43 and operatively related to the recesses 38 of the tapes 37, and that the slats are supported in spaced operative position adjacent the lower portion of the device. It will be observed also that the present invention provides novel means for tilting and retaining the slats in various desired positions of inclined adjustment.

Obviously, the present invention is not limited to the precise construction and arrangement shown and described, as the same may be variously modified. Moreover, all of the features of the present invention need not be used conjointly, as the same may be used to advantage in variously different combinations and subcombinations.

What I claim as new and desire to cover by Letters Patent is:

1. In a device of the class described, slat supporting means windable on a roller, said supporting means having spacing means associated therewith, a plurality of slats, brackets connected to said slats and relatively movable with respect to said supporting means, and means carried by said brackets and cooperable with the spacing means and said supporting means for supporting the brackets and slats on and in spaced relation longitudinally of said supporting means.

2. In a device of the class described, slat supporting means windable on a roller, said supporting means having spaced cut-away portions formed therein, a plurality of slats, brackets connected to said slats and relatively movable with respect to said supporting means, and connecting means carried by said brackets and cooperable with the respective cut-away portions of said supporting means for supporting the brackets and slats on and in spaced relation longitudinally of said supporting means.

3. In a device of the class described, a plurality of slat supporting tapes windable on a roller, said tapes having a plurality of spaced recesses formed therein, a plurality of slats, a plurality of brackets connected to the respective slats and relatively movable with respect to said supporting tapes, and means pivotally mounted on said brackets and cooperable with the respective recesses for supporting the brackets and slats in spaced relation longitudinally of said tapes.

4. In a device of the class described, a plurality of slat supporting tapes windable on a roller, said tapes having a plurality of spaced recesses formed therein, a plurality of slats, a plurality of brackets carried by the respective slats and relatively movable with respect to said supporting tapes, and connecting means mounted on said brackets and operatively related to the respective recesses for connecting the brackets to said tapes and supporting the brackets thereon in spaced relation longitudinally thereof, and means on the respec-

tive brackets and operatively related to the connecting means on adjacent brackets for disconnecting the brackets from the tapes and supporting adjacent brackets in juxtaposition.

5. In a device of the class described, the combination of a supporting frame, a roller rotatably mounted thereon, a plurality of slat supporting tapes wound on said roller, a plurality of tape guides mounted on said frame, said tapes having a plurality of spaced recesses formed therein, a plurality of slats, a plurality of brackets carried by the respective slats and relatively movable with respect to said supporting tapes, and connecting means pivotally mounted on said brackets and operatively related to the respective recesses formed in said tapes for connecting the brackets to the tapes and supporting the brackets thereon in spaced relation longitudinally thereof, and means mounted on said tape guides and the respective brackets and operatively related to the connecting means on adjacent brackets for disconnecting the brackets from the tapes and supporting adjacent brackets in juxtaposition adjacent the upper portion of the device.
25. In a device of the class described, the combination of a supporting frame, a roller rotatably mounted thereon, a plurality of slat supporting tapes having a plurality of spaced recesses formed therein wound on said roller, a plurality of tape guides mounted on said frame, a plurality of slats, a plurality of brackets carried by the respective slats, supporting means on said tape guides and brackets, and connecting means on said brackets cooperable with said supporting means and said tapes for supporting and retaining the brackets and slats in a group in juxtaposition adjacent the upper portion of the device, said connecting means being adapted to be received by the respective recesses formed in the respective tapes for moving the lowermost slats successively from the group and into spaced position adjacent the lower portion of the device as the tapes are drawn from said roller.
7. In a device of the class described, the combination of a supporting frame, a roller rotatably mounted thereon, a plurality of slat supporting tapes having a plurality of spaced recesses formed therein wound on said roller, a plurality of tape guides mounted on said frame, a plurality of superposed slats, a plurality of brackets carried by the respective slats, supporting means on said tape guides and brackets, connecting means on said brackets cooperable with said supporting means and said tapes for supporting and retaining the brackets and slats in a group in inoperative juxtaposition adjacent the upper portion of the device, said connecting means being adapted to be received by the respective recesses formed in the respective tapes for moving the lowermost slats successively from the group and into spaced operative position adjacent the lower portion of the device as the tapes are drawn from said rollers, and means for urging said connecting means toward said tapes.
65. In a device of the class described, the combination of a supporting frame, a roller rotatably mounted thereon, a plurality of slat supporting tapes having a plurality of spaced recesses formed in one of their edge portions wound on said roller, a plurality of tape guides mounted on said frame, a plurality of superposed slats, a plurality of brackets secured to the edge portions of the respective slats, supporting means on said tape guides and brackets, connecting means on said brackets pivotally mounted on said brackets and

cooperable with said supporting means and said tapes for supporting and retaining the brackets and slats in a group in inoperative juxtaposition adjacent the upper portion of the device, said connecting means being adapted to be received by the respective recesses formed in the edge portions of the respective tapes for moving the lowermost slats successively from the group and into spaced operative position adjacent the lower portion of the device as the tapes are drawn from the roller, and means for urging said connecting means toward the recessed edges of said tapes.

9. In a device of the class described, the combination of a tiltable supporting frame, a roller rotatably mounted thereon, a plurality of slat supporting tapes having a plurality of spaced recesses formed in one of their edge portions wound on said roller, a plurality of tape guides pivotally mounted on said frame, a plurality of superposed slats, a plurality of brackets carried by the longitudinal edge portions of the respective slats and pivotally related thereto, supporting means on said tape guides and brackets, connecting means pivotally mounted on said brackets, and cooperable with said supporting means and said tapes for supporting and retaining the brackets and slats in a group in inoperative juxtaposition adjacent said frame and the upper portion of said device, said connecting means being adapted to be received by the respective recesses formed in the edge portions of the respective tapes for moving the lowermost slats successively from the group and into spaced operative position adjacent the lower portion of the device as the tapes are drawn from said roller, means for urging said connecting means toward the recessed edges of said tapes, and means for tilting said supporting frame and slats laterally and in substantially parallel relation laterally with respect to each other.

10. In a device of the class described, a supporting frame having a sheave adjacent one end thereof, a spring roller rotatably mounted in said frame, a plurality of tapes having a plurality of spaced recesses formed therein wound on said roller, a plurality of superposed slats, a plurality of brackets carried by the respective slats and pivotally related thereto, connecting means on said brackets operatively related to the respective recesses formed in said tapes for supporting said brackets and slats thereon in spaced relation longitudinally thereof, and means operatively related to said sheave for rotating said supporting frame and tilting said slats laterally in substantially parallel relationship with respect to each other.

11. In a device of the class described, a supporting frame having a sheave adjacent one end thereof, a spring roller rotatably mounted on said frame, a plurality of tape guides and guide rollers pivotally mounted on said frame at opposite sides of said spring roller, a plurality of tapes having a plurality of spaced recesses formed therein wound on said spring roller and extending laterally therefrom at opposite sides thereof and through and over said tape guides and guide rollers, respectively, a plurality of superposed slats, a plurality of brackets carried by the respective slats and pivotally related thereto, connecting means on said brackets operatively related to the respective recesses formed in said tapes for supporting said brackets and slats thereon in spaced relation longitudinally thereof, and means operatively related to said sheave for rotating said supporting frame and tilting said

slats laterally in substantially parallel relationship with respect to each other.

12. In a device of the class described, a supporting frame having a sheave adjacent one end thereof, a spring roller rotatably mounted in said frame, a plurality of tape guides and guide rollers pivotally mounted on said frame at opposite sides of said spring roller, a plurality of tapes having a plurality of spaced recesses formed therein wound on said spring roller and extending laterally therefrom at opposite sides thereof and through and over said tape guides and guide rollers, respectively, a plurality of superposed slats, a plurality of brackets carried by the respective slats and pivotally related thereto, connecting means on said brackets operatively related to the respective recesses formed in said tapes for supporting said brackets and slats thereon in spaced relation longitudinally thereof, a bearing member, a drum having a cable wound thereon rotatably mounted in said member, said cable being operatively related to said sheave for rotating said supporting frame and tilting said slats laterally in substantially parallel relationship with respect to each other, means for rotating said drum, and means for securing said drum in various positions of adjustment.

13. In a device of the class described, a supporting frame having a sheave adjacent one end thereof, a spring roller rotatably mounted in said frame, a plurality of tape guides and guide rollers pivotally mounted on said frame at opposite sides of said spring roller, a plurality of metallic tapes having a plurality of spaced recesses formed in one of their edge portions wound on said spring roller and extending laterally therefrom at opposite sides thereof, and through and over said tape guides and guide rollers, respectively, a plurality of substantially parallel superposed slats, a plurality of brackets carried by the respective slats and pivotally related thereto, connecting means on said brackets operatively related to the respective recesses formed in said tapes for supporting said brackets and slats thereon in spaced relation longitudinally thereof, a drum having a cable wound thereon rotatably mounted in said member, said cable being operatively related to said sheave for rotating said supporting frame and for tilting said slats laterally in substantially parallel relationship with respect to each other, manually actuated means for rotating said drum, and spring actuated means for yieldingly securing said drum in various positions of adjustment.

14. In a device of the class described, the combination of a tape having recesses formed therein, a slat, means for connecting said slat to said tape, said means comprising a bracket carried by said slat, an arm pivotally mounted on said bracket, a connecting pin adjacent one end of said arm adapted to engage a recess in said tape, and means associated with said arm for urging said pin toward said tape.

15. In a device of the class described, the combination of a flexible tape having recesses formed in one of its edge portions, a slat, means relatively movable longitudinally of said tape for connecting said slat thereto, said means comprising a bracket carried by said slat and pivotally related thereto, an arm pivotally mounted on said bracket, a connecting pin and a trip pin adjacent one end of said arm, said connecting pin being adapted to engage a recess in said tape, and means associated with said arm for urging said connecting pin toward the recessed edge of said

tape, said trip pin being adapted to be engaged by a portion of an adjacent bracket for moving said connecting pin out of said recess.

16. In a device of the class described, the combination of a plurality of flexible tapes having spaced recesses formed in one of their respective edge portions, a plurality of slats, means slidably mounted on said tapes for connecting the respective slats thereto, said means comprising brackets carried by said slats, arms pivotally mounted on the respective brackets, a connecting pin and a trip pin adjacent one end of each of said arms, said connecting pins being adapted to engage the recesses formed in the respective tapes, means associated with said arms for urging the connecting pins toward the recessed edge of the associated tapes and into said recesses, and a trip lug on each of said brackets, each of said lugs having a laterally disposed notch adjacent the recessed edge of the associated tapes, each of said lugs being adapted to engage the trip pin on the arm of its adjacent bracket for moving the connecting pin out of its recess and into one of said notches.

17. In a device of the class described, the combination of a plurality of flexible tapes having spaced recesses formed in one of their respective edge portions, a plurality of slats, means slidably mounted on said tapes for connecting the respective slats thereto, said means comprising brackets carried by said slats and pivotally related thereto, arms pivotally mounted intermediate their ends on the respective brackets, a connecting pin and a trip pin adjacent one end of each of said arms, said connecting pins being adapted to engage the recesses formed in the respective tapes, weights on the opposite ends of said arms for urging the connecting pins toward the recessed edge of said tapes and into said recesses when the recesses are brought into register therewith, and a lug on each of said brackets, each of said lugs having a laterally disposed notch adjacent the recessed edge of the associated tapes, each of said lugs on their respective bracket being adapted to engage the trip pin on the arm of its respective subjacent bracket for moving the connecting pin of the arm on said subjacent bracket out of said recess and into said notch against the action of said weight, the unrecessed portions of the associated tapes cooperating with said lug for holding the connecting pin in said notch for supporting said subjacent bracket.

18. In a Venetian blind, means for mounting the slats thereof on a flexible tape, comprising a strip of flexible material having upwardly extending inturned end portions adapted to engage the opposite longitudinal edge portions of a slat, and laterally extending inturned trunnions secured to the opposite ends of said strip and adapted to pivotally engage supporting brackets at the respective longitudinal edge portions of said slat.

19. In a device of the character described, a plurality of tapes adapted to hang from supporting rollers, a plurality of slats slidably mounted on each of said tapes by means of brackets, and means associated with said brackets to releasably and pivotally secure said slats relative to each of said tapes.

20. In a device of the character described, a pair of tapes extending laterally from and windable on opposite sides of a supporting roller, a plurality of slats releasably associated with each of said tapes, and means to reduce the downward extension of the length of one of said tapes on which said slats are releasably associated with respect to the other of said tapes.

21. In a Venetian blind, a flexible tape for the support of slats thereof having lateral notches.
22. In a Venetian blind, means for releasably retaining the slats thereof, comprising a plurality of brackets, each of said brackets being adapted to engage subjacent brackets.

23. In a device of the character described, a plurality of tapes, a plurality of slats slidable on said tapes and means to releasably support said slats equi-distantly along said tapes relative to each other.

LEE R. ROBERTS.
